Inventor

David Arthur Barlow.

UNITED STATES PATENT OFFICE

DAVID ARTHUR BARLOW, OF PHILADELPHIA, PENNSYLVANIA

ELECTRIC GAS LIGHTER

Application filed October 19, 1927. Serial No. 227,321.

This invention appertains to new and useful improvements in circuit makers and breakers, and more particularly to a novel switch especially adapted for use in conjunction with electric gas lighters, such as are adapted to be mounted on electric ranges.

An important object of the invention is to provide a switch which will be of low cost of manufacture, and which will in use be positive acting and not susceptible to the development of defects which would tend to occur in a more complicated structure.

Various other important objects of the invention will become more apparent to the reader after the following specification is read.

In the drawings:—

Figure 1 represents a side elevational view of the switch mount.

Fig. 2 represents a side elevation of the switch mount showing the reverse side from that shown in Fig. 1.

Fig. 3 represents a cross sectional view through the switch housing showing the switch mount therein.

Fig. 4 represents an edge elevational view of the switch mount.

Referring to the drawings wherein like numerals designate like parts, it can be seen that the base A has a hard rubber strip B attached across the top by means of screws B' and B''. This holds the contact spring F and acts as one contact point from the primary electric current. The base A also has a suitable hole for the shaft B which operates the lever G by a clockwise turn of the knob C.

Attached to the threaded end of the shaft B is the spring D' the same extending through a small hole at a point midway of the shaft D and connects in the screw D'' on the base A. But the shaft D and the lever G returns to normal position and the spring acts as a conductor for the primary current from the screw D'' thus completing the primary circuit when the knob C, shaft D and lever G are turned clockwise.

The screw D'' also acts in the lever G to the shaft D. The lever G has a central open-

ing which receives the shaft D and is secured to the shaft D by the set screw G''. The lever G and the copper wire along the under side thereof, which is supported in place by inserting the ends thereof through openings at one end and the center thereof. This acts as a connecting rod for the secondary high tension current which closes the circuit between E and A', A'', A'', A'', A'', and A'' when the shaft D is turned clockwise.

A stop G''' is employed for the lever G and against this, the lever may normally engage, and as can be clearly shown in the drawing, the stop G''' is provided for the lever G when the latter is at its opposite extent of travel.

The contact points A', A'', A'', A'', and A'' are constructed of small pins or screws secured at a specified distance apart, and from the contact G''' so as not to allow sparking.

Fig. 3 shows the complete switch as is also shown in Figs. 2 and 4, and the casing for the switch is denoted by numeral I and is secured to the gas pipe of the range by means of the clamp H.

The clamp H is grounded by a wire to the screw F' extending from the spring F. In operation the gascock on the range or stove, for controlling the gas burner is turned on in the usual manner, and subsequently to this, the switch is turned on to close the primary battery circuit. Thus a spark is produced across the range burner, igniting the gas at the particular burner from which gas is issuing.

Having thus described my invention, what I claim as new is:—

In an electric switch comprising, a base, a shaft journaled through the base and being adapted to project beyond opposite sides thereof, an arm secured to one end of the shaft, a spring contact on the base, a rigid contact on the said arm adapted for wiping engagement with the said spring contact, an elongated contact strip engaged longitudinally on the arm, an arcuate contact strip on the base, and a plurality of contact members on the base arranged concentrically with respect to the arcuate contact strip, said con-

tacts being adapted to be successively bridged with the arcuate strip by the longitudinally disposed contact strip on the arm.

In witness whereof I have hereunto set my hand at Philadelphia, in the county of Philadelphia and State of Pennsylvania, this 31st day of August, 1927.

DAVID ARTHUR BARLOW. [L. S.]
